UNITED STATES PATENT OFFICE.

JOHN H. HARMSTONE, OF ATTLEBORO, MASSACHUSETTS, ASSIGNOR TO FESSENDEN AND COMPANY, INC., OF PROVIDENCE, RHODE ISLAND, A CORPORATION OF RHODE ISLAND.

DESIGN FOR THE HANDLE OF A SPOON, FORK, OR SIMILAR ARTICLE.

50,103.

Specification for Design.

Patented Dec. 26, 1916.

Application filed September 1, 1916. Serial No. 118,154. Term of patent 3½ years.

To all whom it may concern:

Be it known that I, JOHN H. HARMSTONE, a citizen of the United States, residing at the city of Attleboro, county of Bristol, and State of Massachusetts, have invented a new, original, and ornamental Design for the Handle of a Spoon, Fork, or Similar Article, reference being had to the accompanying drawing, forming a part thereof.

The figure is a front view of the handle

for a spoon, or fork illustrating my new design.

I claim:

The ornamental design for the handle of a spoon, fork, or similar article as shown.

JOHN H. HARMSTONE.

Witnesses:

ALBERT E. HATHAWAY,
HENRY H. LEWIS.
